UNITED STATES PATENT OFFICE.

IRWIN ROPP, OF NEW BEDFORD, PENNSYLVANIA.

PLAYING CARDS.

Application filed August 9, 1924. Serial No. 731,155.

To all whom it may concern:

Be it known that I, IRWIN ROPP, a citizen of the United States, residing at New Bedford, in the county of Lawrence and State 5 of Pennsylvania, have invented a new and useful Improvement in Playing Cards, of which the following is a specification.

In the accompanying drawing there is shown one of the State cards, the aeroplane 10 card and the steamship card.

This game consists of fifty (50) cards. Each of forty-eight (48) of these cards has printed on its face, the map of one of the forty-eight States of the United States. In 15 addition to the map, it has the letter "A" and a number which corresponds to the rank of that State in land area, the State with the smallest area having the number one (1) and the State with the largest area, the number forty-eight (48).

In addition to the map, letter, and number described, each card also has the letter "P" and a number which corresponds to the rank of that State in population, according to the last official census of the 25 United States, the State with the smallest population having the number one (1) and the State with the largest population the number forty-eight (48).

One (1) card has printed on its face the 30 picture of an aeroplane.

One (1) card has printed on its face the picture of an ocean steamer.

A number of games may be played with 35 these cards, one of which is as follows:

Seven cards are dealt to each player. The player to the left of the dealer decides whether play is to be for area or population. The next player orders either 40 "play" or "discard".

If "play" is ordered, each player makes a journey of the cards he holds, the one with the greatest number of points winning the trick.

In making a journey, only adjoining 45 States can be used. Example: Iowa, Illinois, Kentucky, Ohio. The ocean steamer may be used to join two States bordering on the ocean. Example: Idaho, Washington—Steamer—Virginia, Tennessee. The 50 aeroplane may be used to join any two States. Example: New York—Aeroplane—Missouri.

If "discard" is ordered, each player, beginning with the one who orders, may discard any cards he holds and draw from the deck as many as he discards. Discards 55 are placed face up on the table and may be drawn by any succeeding player, instead of cards from the deck.

Players order in turn until "play" is ordered, when each makes a journey as previously described.

The first player winning three tricks wins 65 the game.

Having described my invention, what I claim is:

A game of playing cards consisting of maps of the 48 States of the United States, together with numbers representing the 70 inverse of the rank of each State in area and population, and two cards having pictures of an ocean steamer and an aeroplane.

IRWIN ROPP.
